(57) **CLAIM**

The ornamental design for a hair clipper, as shown and described.

DESCRIPTION

FIG. 1 is a front and left perspective view of a hair clipper, showing my design.

FIG. 2 is back and right perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of portion "9" shown in FIG. 1; and,

FIG. 10 is an enlarged view of portion "10" shown in FIG. 2.

The evenly spaced broken lines in the figures illustrate portions of the article which form no part of the claim. The dot-dash broken lines illustrate enlarged view indicators and form no part of the claimed design.
